CAMERA FLASH ATTACHMENT

Raymond A. Grosso, Troy, Mich., assignor to Minnesota Mining and Manufacturing Company, St. Paul, Minn., a corporation of Delaware

Filed Jan. 26, 1970, Ser. No. 21,079

Term of patent 14 years

Int. Cl. D16—07

U.S. Cl. D61—1

FIG. 1

FIG. 2

FIG. 3

FIG. 4

FIG. 5

FIG. 1 is a top view of a camera flash attachment of my new design;

FIG. 2 is a bottom view of a camera flash attachment of my new design;

FIG. 3 is an elevational view of the front of a camera flash attachment of my new design;

FIG. 4 is an elevational view of one side of a camera flash attachment of my new design, the opposite side of a camera flash attachment of my new design having the same appearance; and

FIG. 5 is an elevational view of the back of a camera flash attachment of my new design.

I claim:

The ornamental design for a camera flash attachment, substantially as shown and described.
